UNITED STATES PATENT OFFICE.

GEORGE F. JONES, OF FAIRFIELD, ILLINOIS.

HOSE-CLAMP.

1,282,848.

Specification of Letters Patent. Patented Oct. 29, 1918.

Application filed October 13, 1917. Serial No. 196,448.

To all whom it may concern:

Be it known that I, GEORGE F. JONES, a citizen of the United States, residing at Fairfield, in the county of Wayne and State 5 of Illinois, have invented new and useful Improvements in Hose-Clamps, of which the following is a specification.

This invention relates to clamping devices especially adapted for use in connection 10 with hose couplings, although the device may be equally well adapted for clamping hoops upon wooden silos or for other purposes.

The object of the invention is to provide 15 novel means for tensioning and holding in position a flexible element used for the purposes above set forth, the said means including a frame provided with a concaved base and parallel bearing arms in which is 20 mounted for rotation an adjusting key, means being provided for holding the key in its adjusted position, the frame being further provided upon each of its side edges 25 with guiding notches to receive and guide the flexible element.

In the drawings,

Figure 1 is a perspective view of the invention in use;

Fig. 2 is a transverse sectional view of the 30 same; and

Fig. 3 is a central longitudinal sectional view.

Fig. 4 is a detailed view of the modified 35 form of key upon which there is provided a squared projection for the reception of a wrench; and

Fig. 5 is a view of a still further modified form having an opening in the finger piece for the reception of the punch or other 40 instrument.

In the drawings, there is illustrated a coupling member 10, which is designed to couple two sections of a hose, one of such sections being indicated at 11.

45 The clamping or tensioning device consists of a frame provided with a base 12, the under face of which is concave as shown at 13. This base is provided at each end with parallel bearing arms 14, having alined

bearing openings 15, in which is mounted 50 for rotation an adjusting key 16. The inner end of this key is provided with a finger piece 17 and between this finger piece and the adjacent bearing arm the key has formed 55 therein or secured thereto a ratchet wheel 18. Mounted upon the bearing arm for engagement with the ratchet wheel 18 is a pawl 19, which is adapted to engage the teeth of the said wheel to hold the key 16 in its adjusted position.

The key 16 is formed in that portion which lies between the parallel bearing arms 14 with the opening 20, which is adapted to receive both ends of a flexible element 21, which is preferably in the form of a 60 wire. This element is adapted to be passed around the coupling member in a manner to form a double loop, the strands of one loop being received and guided in the notches 22 formed in the opposite side edges 65 of the base 12.

In the operation of the device, the flexible element or wire is placed upon the coupling member 10 in the manner above described and the key 16 rotated for tightening and 70 tensioning said element sufficiently to retain said coupling member in position, the said flexible element being maintained in its tensioned condition by means of the pawl 75 and ratchet wheel described.

Various changes may be made in the form, proportion and minor details of construction of the device and the right is reserved to make such changes.

Having described the invention, what is 80 claimed is:

1. Means for clamping two pipes together comprising in combination a frame including a base and spaced parallel side arms, legs extending below said base to space the 85 bottom face of the latter from a support to define a passage, an adjusting key rotatably mounted in said arms, a loop flexible element engaging said key, whereby rotation of the latter will enlarge or reduce the loop and 90 means carried by the key and engageable with means carried by the frame for holding 95 the key in its adjusted position.

2. A clamp comprising in combination a frame including a blade and spaced parallel side arms, lugs extending below said base to space the bottom face of the latter from a support and defining a passage, an adjusting key rotatably mounted in said arms, a looped flexible element engaging said key,

whereby the rotation of the latter will enlarge or reduce the loop, means for holding the key in its adjusted position and guiding 10 notches formed in opposite edges of the face for guiding the flexible element.

In testimony whereof I affix my signature.
GEORGE F. JONES.
